PIE SECTIONING DEVICE

Melvina F. Sellors, Los Angeles, Calif.

Application August 19, 1954, Serial No. 31,937

Term of patent 14 years

(Cl. D44—29)

Fig 1

Fig 2

To all whom it may concern:

Be it known that I, Melvina F. Sellors, a citizen of the United States, residing at Los Angeles, in the county of Los Angeles and State of California, have invented a new, original, and ornamental Design for a Pie Sectioning Device, of which the following is a specification, reference being had to the accompanying drawing, forming part thereof.

Fig. 1 is a perspective view of a pie sectioning device showing my new design; and

Fig. 2 is a sectional view taken along line 2—2 of Fig. 1.

I claim:

The ornamental design for a pie sectioning device, substantially as shown.
